CLAIM

The ornamental design for a food bowl for pets, as shown and described.

DESCRIPTION

FIG. 1 is a perspective view of a food bowl for pets, showing my new design;

FIG. 2 is a front elevation view thereof;

FIG. 3 is a back elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines illustrate portions of the food bowl for pets that form no part of the claimed design.
